UNITED STATES PATENT OFFICE.

GEORGE PETER, OF NEW YORK, N. Y.

SCRAPER-SHARPENER.

SPECIFICATION forming part of Letters Patent No. 347,506, dated August 17, 1886.

Application filed June 22, 1886. Serial No. 205,854. (No model.)

To all whom it may concern:

Be it known that I, GEORGE PETER, of the city of New York, county and State of New York, have invented a new and Improved 5 Scraper-Sharpener, of which the following specification is a full, clear, and exact description.

This invention relates to a sharpener for scrapers; and it consists in the various features 10 of improvements hereinafter more fully described.

In the accompanying drawings, Figure I represents a side view, and Fig. II a plan or top view, of my improved machine. Fig. III is a 15 cross-section on line $x-x$, Fig. II.

a is the bed-plate provided with feet p at the ends, through which the same is attached to the bench or table.

b is a support embracing the side edges of 20 the bed-plate a , and capable of sliding freely back and forth on the same. The upper part of this support is made in two parts, $b' b'$, fastened together by bolts $c c$, and provided with steel plates $d d$, inserted on their inner edges 25 and roughened at their inner sides to hold the scraper S , which is clamped between these two parts firmly in its place.

Upon the top of the bed-plate a a perfectly- 30 straight metal plate, w , is fastened parallel with the edges of the bed-plate upon which the support slides.

In the middle of the bed-plate a a frame, f , is arranged, the two legs of which pass through the bed-plate a and plate w , and are provided 35 with movable guiding-pieces h , resting upon the top of the plate w , and secured by means of set-screws i . These guiding-pieces h are regulated to correspond with the width of the 40 scraper S to guide the same sidewise and act at the same time to keep the frame f in its place. The central part of this frame f sup-

ports a block, k , carrying on its upper end the cutter-wheel m . This block k , with its wheel, passes through the center of the bed-plate a and metal plate w , so as to bring the edge of 45 the wheel m in line with the upper surface of the metal plate w .

Below the shank k' of the block k a set-screw, n , is placed, for raising or lowering the block, and consequently the wheel m , as may be desired. Near this wheel m guides $v v$, arranged diagonally, are attached to the metal plate w , to guide the scraper S in its proper direction.

The operation is as follows: The scraper S , the edge of which has been previously 55 strengthened, is clamped, with its straight edge resting upon the metal plate w , between the two upper plates $b' b'$ of the support b , and securely fastened by the bolts $c c$. The support, together with this scraper, is then 60 passed several times backward and forward over the cutter-wheel m , where its receives the desired cutting-edge. The fixed guides $v v$ bring the lower part of the scraper directly over the wheel m , while the guiding-pieces h 65 hold the same steady sidewise.

What I claim is—

1. In combination with the bed-plate a and support b , the frame f , with guiding-pieces h h , and cutting-wheel m , substantially as and 70 for the purpose set forth.

2. In combination with the bed-plate a , provided with a metal plate, w , and frame f , the cutting-wheel m , supported in a block, k , and the set-screw n , acting against the shank k' of 75 the block k , substantially as and for the purpose described.

GEORGE PETER.
